UNITED STATES PATENT OFFICE.

GEORGE C. EMMERT, OF MOUNT MORRIS, ILLINOIS.

SLIDING-DOOR LATCH AND LOCK.

No. 810,927.

Specification of Letters Patent.

Patented Jan. 30, 1906.

Application filed May 15, 1905. Serial No. 260,367.

To all whom it may concern:

Be it known that I, GEORGE C. EMMERT, a citizen of the United States, residing at Mount Morris, in the county of Ogle and State of Illinois, have invented certain Improvements in Sliding-Door Latches and Locks, of which the following is a specification.

This invention relates to certain improvements in that class of latches and locks which are more particularly designed and adapted for use in connection with sliding or rolling doors; and the object of the invention is to provide a latch and lock of this general character of a simple and inexpensive nature and of a strong, compact, and durable construction, wherein there is no projection of the bolt beyond the door when unlatched and wherein means of an improved and simplified character are provided for throwing the latch-bolt to cause it to protrude from the door in latching position and for retracting said bolt flush with the door when the door is unlatched.

The invention consists in certain novel features of the construction, combination, and arrangement of the several parts of the improved door latch and lock whereby certain important advantages are attained and the device is rendered simpler, cheaper, and otherwise better adapted and more convenient for use, all as will be hereinafter fully set forth.

The novel features of the invention will be carefully defined in the claims.

In the accompanying drawings, which serve to illustrate my invention, Figure 1 is a fragmentary view showing portions of the meeting stiles of double sliding doors provided with a latch and lock device embodying my improvements, and Fig. 2 is an enlarged sectional view taken on line *a-a* of Fig. 1. Fig. 3 is a fragmentary view showing a portion of the rear surface of the escutcheon-plate, together with the operating-slide carried thereby. Fig. 4 is a sectional view taken vertically through the latch-casing and showing the several parts of the improved latch in retracted or unlocked position. Fig. 5 is a view somewhat similar to Fig. 4 with certain parts of the device broken away and showing the latch device with its operative parts thrown into latching position. In this view is also shown a fragment of the door-stile, together with a part of the door-jamb, whereon are held the latch-plate and certain parts connected therewith for engagement with the latch-bolt when thrown into latching posi-

tion. Fig. 6 is a view similar to Fig. 5, but illustrating the operative parts of the latch when moved in position to release and retract the latch-bolt. Fig. 7 is a view similar to Figs. 5 and 6, but showing certain locking devices comprised in the improved latch in the position in which they stand when operated to lock the latch-bolt. Fig. 8 is an enlarged under side view of the latch-bolt, together with the several operative parts carried thereon. Fig. 9 is a face view showing a door-plate especially adapted for use in connection with the latch device. Fig. 10 is a fragmentary sectional view showing a casing connected with the latch-plate and adapted for use in connection with double sliding doors. Fig. 11 is a view showing detached the adjustable auxiliary latch-plate carried by the door-plate seen in Fig. 10.

Referring first to Fig. 1 of the views, 1 and 2 represent two sliding doors, the stiles of which are adapted when the doors are closed to fit flush upon each other, and 3 and 4 represent escutcheon-plates held upon the stiles of the doors in a well-known way and provided with central recessed portions 5, which are let into opposite sides of the respective stiles, as seen in Fig. 2. For use in connection with such double sliding doors metal casings 13 are preferably provided, which are mortised into the edge of the stile between the escutcheons, as seen in Fig. 2, the casing 13 of one of said doors—as, for example, the door 1—containing the latch-bolt, with its operating and locking mechanisms, while the casing for the door 2 contains the devices for engagement with the latch-bolt when thrown into latching position and is connected with the latch-plate having an adjustable auxiliary plate, as will be hereinafter explained. In the case of a single sliding door the last-mentioned casing may be omitted, the latch-plate and bolt-engaging parts connected therewith being mounted upon the jamb in position for engagement with the latch-bolt.

The central recessed portions 5 of the escutcheons form convenient finger-holds, by means of which the door may be readily moved or slid into opened or closed position. Within said recessed parts of the escutcheons of the door 1 are extended ears or projections 6, produced upon actuating-slides 8, which are arranged for sliding movement transversely across the under or rear faces of the inwardly-directed portions of the escutcheons, being connected by outwardly-extend-

ed parts 77 with said ears or projections 6. The ears 6 are located at the walls of recesses 5, which are adjacent to the edge of the door-stile, and said walls are preferably hollowed out around the said ears or projections, so that when pressure of the fingers is exerted upon said ears they may be pressed far enough through said walls of the recesses 5 of the escutcheons for the operation of the latch mechanisms, as will be hereinafter explained.

99 indicate sockets produced upon the actuating-slides 88 and directed toward the opposite surfaces of the casing 13, within which the operative latch mechanisms are held, said sockets being adapted to receive pins or studs 1111, projecting through slotted openings 12 in the opposite walls of the casing, being carried upon a lever 14, pivoted, as seen at 15 in Fig. 4, at the lower part of the casing and adapted when moved to traverse a path alined with the direction of movement of the door itself when slid into opened and closed position. The lever 14 has its upper end adapted for engagement with certain devices upon the latch-bolt 19, which is guided for movement across the upper part of the casing, whereby said latch-bolt may be thrown in and out of latching position. The upper part of said lever 14 has also a curved portion 17, concentric with the key-apertures 18 in the casing and escutcheons 33, so that keys inserted at said apertures may be freely turned without contact with said lever. 16 is a spring within the casing for holding said lever in retracted position, as seen in Fig. 4, and said spring will also serve to hold the ears or projections 66 of the actuating-slides pressed into the recesses 5 in position for being conveniently engaged by the fingers.

40 The latch-bolt 19 is adapted for movement in a direction parallel with the path of the door when moved into opened or closed position, and the casing 13 is provided with a door-plate 38, adapted to be let into the edge 45 of the door-stile, as seen in Fig. 5, said door-plate 38 being provided with an opening 20, through which the extremity of the latch-bolt is adapted to play when moved into latching position. When the latch-bolt 19 is retracted, as seen in Fig. 4, its extremity fits snugly in said opening 20 to close the same, and the end surface of said bolt is flush with the door-plate 38, so that there is no protrusion of the bolt such as might strike or catch 55 upon persons passing the door or might be accidentally bent or broken to impair the utility of the device.

The extremity of the latch-bolt 19 is formed with a downwardly-directed hook-like part 21, whereby an opening or space 22 is produced beneath said bolt at the rear of said hook-like part 21, and said downwardly-directed part 21 of the bolt is adapted for engagement with certain devices to be hereinafter explained for holding the bolt in latched

position, while the opening or space 22 is adapted for the movement of certain releasing devices, whereby the latch-bolt may be released from said engaging devices and may be retracted within the casing 13. The 70 latch-bolt 19 has a rear end portion 23 of reduced thickness, there being a shoulder 24 at the forward part of said reduced end portion and at one side of the bolt, as seen in Figs. 4, 5, 6, and 8, and a spring 33 has engagement 75 with a pin at said reduced end 23 of the bolt in such a way that its tension is exerted to retract said bolt when released within the casing 13 in the position seen in Fig. 4. The latch-bolt 19 is also provided with downwardly-directed spaced lugs or forks 25 near its forward part, and the lower ends of said forks or arms 25 are engaged to slide when the bolt is thrown and retracted upon a ledge 26 in the casing. At the upper part of the 80 bolt 19 above the forks 25 there is produced a rearwardly-directed lug or shoulder 27, projecting from one side of the bolt, with its under side adapted for engagement with the forward end of a dog 29, pivotally held upon 85 the side of the bolt, with a weighted rear end 31, which when said dog stands in its normal position, with its forward end 28 engaged beneath the shoulder 27, is adapted to depend in the position shown in Figs. 4 and 5, so as 90 to be engageable by the pointed upper extremity 32 of lever 14, whereby it will be evident that when said lever is moved by means of either of the actuating-slides 8, as above explained, its upper end 32 will come into engagement with the weighted extremity 31 of the dog 29 upon the side of the latch-bolt, so that the movement of said upper end of the lever will be communicated to the bolt to throw the hook-like extremity 21 of the same 100 out beyond the door-plate 38 to the position shown in Figs. 5 and 6.

Where the improved latch device is used in connection with single sliding doors the arrangement of latch-plate and bolt-engaging means shown in Fig. 5 will be preferably employed, and, if desired, this arrangement may also be used in connection with double sliding doors. As shown in said figure, there is a latch-plate 41 let into the door-jamb and held in place by means of screws or the like and provided with an opening 42, formed in it in substantial alinement to receive the projecting end 21 of the latch-bolt when thrown, said opening 42 being, however, of a length 115 sufficient to extend considerably above and below the extended end of the bolt, so that the latter will traverse the opening without necessity of accurate measurement in applying the plates 38 and 41 to the door and jamb. 120

43 represents an auxiliary adjustable latch-plate mounted for sliding movement lengthwise upon the rear surface of the plate 41 and provided with an opening 44, adapted for alinement with the opening 42 in plate 41, 125 130

but of a size adapted to snugly receive the hook-like end 21 of the latch-bolt when the same is thrown through said opening 42 in plate 41. At points opposite the screw attachments of the plate 41 the auxiliary plate 43 is provided with slotted openings 45, adapted to permit longitudinal adjustment of said auxiliary plate relatively to plate 41 when the screws of the latter are loosened, whereby the opening 44 in the auxiliary plate 43 may be adjusted to stand higher or lower without requiring resetting of plate 41 to compensate for inaccuracies of measurement in applying the parts to the door and jamb. In this way it will be seen that the auxiliary plate 43 may be raised or lowered sufficiently to permit its opening 44 to properly receive the hook-like end 21 of the latch-bolt when the same is thrown. 34 indicates an auxiliary bolt mounted for vertical sliding movement upon the rear surface of the auxiliary plate 43, with a beveled upper end extended normally above the lower edge of opening 44 in line with the path of the hook-like end 21 of the latch-bolt, so that the latter when thrown will ride freely over said beveled end of the auxiliary bolt 34 in passing through opening 44. The auxiliary bolt 34 is guided, as seen at 35, on the plate 43 and has a stem 36, whereon is coiled a spring 37, by means of which the auxiliary bolt is normally held uplifted, but is adapted to be depressed when engaged by the hooked end 21 of the latch-bolt. After the hooked end of the latch-bolt has reached the limit of its outward movement its lower face slips over the auxiliary bolt 34, which is thereupon permitted to rise under tension of spring 37, so that the auxiliary bolt is thereupon engaged in front of the hooked end 21 of the latch-bolt in opening or space 22 in such a way as to prevent retraction of the latch-bolt within casing 13 under tension of spring 33. By this arrangement it will be seen that when the actuating-slide 8 is operated to move lever 14 the latch-bolt will be thrown to cause its hooked end to traverse opening 44 and to be engaged by the auxiliary bolt 34, and thereby held, so that the door will then be securely latched, and in order to permit the door to be again opened it is essential to disengage the auxiliary bolt 34 from the hooked end of the latch-bolt, so that spring 33 may retract the same, for which purpose I employ other mechanism also operated from the actuating-slides 8 and lever 14 and which I will now describe.

The reduced rear end 23 of the latch-bolt 19 forms a guide whereon is adapted for lengthwise sliding movement a slide block or member 46, the lower part of which projects below the said reduced end 23 of the bolt and has support upon a lug 53 in the casing 13, being also provided with a forwardly-extended arm 54, which, as seen in Figs. 4, 6, and 8,

is extended beneath the latch-bolt 19 toward the hooked end thereof and between the lugs or forks 25 25 of the forward portion of said bolt. 55 is a pin extended between said lugs or forks 25 below said arm 54 and serving as a support therefor and also serving as a draft connection by engagement behind a downwardly-directed head 56, provided upon the forward end of the arm for compelling movement of the block or member 46 in unison with the bolt when the same is thrown into latching position.

57 represents a spring coiled on the arm 54 between the lugs 25 and the member 46 and exerting its tension to normally throw the said member 46 rearwardly upon the guide-arm 23 of the latch-bolt, so as to bring the head 56 of arm 54 in engagement with the pin 55; but it will be evident that upon compression of said spring 57 the member 46 may be moved forwardly upon the latch-bolt in such a way as to cause the headed end 56 of its arm 54 to move forward along the opening or space 22 behind the hooked end 21 of the latch-bolt until said headed end 56 of the arm 54 contacts with the beveled surface of the auxiliary bolt 34 in such a way as to depress the same to permit the release of the hooked end of the latch-bolt therefrom, so that the latter may be retracted within casing 13 by spring 33.

58 represents a notch or opening formed in the rear lower part of the hooked end 21 of bolt 19 to receive the extremity of the head 56 of arm 54, so that said head is caused to pass entirely across the top of the auxiliary bolt. In this way the effects of wear of the parts are overcome and the release of the latch-bolt is rendered positive whenever the member 46 is moved upon the guide 23.

59 represents an auxiliary dog pivotally held upon the lateral face of the member 46 and provided with an ear 60 for engagement with a stop projection or lug 61 on said member, so that normally the dog 59 is supported in the position shown in Figs. 4, 5, and 7, with its forwardly-extended arm 62 directed in front of the member 46 and in a plane above the weighted lower end 31 of the dog 29 on the latch-bolt. The auxiliary dog 59 is also provided with a downwardly-extended finger 63, behind which the pointed upper end 32 of the lever 14 is adapted to be engaged when the latch-bolt has been thrown into latching position, the member 46 partaking, of course, of the forward movement of the bolt, so that said finger 63, which before was behind the normal position of lever 14, is moved into position in advance of said lever, as seen in Fig. 7. After the bolt 19 has been thrown into latched position the lever 14, being retracted by its spring, will pass beneath the finger 63, the forward side of which is rounded to produce a cam-surface to facilitate the lifting of the dog on retraction of

said lever. In this way it will be seen that when the latch-bolt is in latching position and lever 14 has been retracted a further forward movement of said lever will serve to 5 impart forward movement to the member 46 relatively to the latch-bolt by engagement of the pointed upper end of such lever with the corresponding finger 63, and in this way the spring 57 will be compressed and the headed 10 end 56 of arm 54 will traverse opening 22 and depress the auxiliary bolt 34 to release the latch-bolt 19, which will be immediately retracted within casing 13 by spring 33; but at the instant of release of the latch-bolt the 15 forward extremity 62 of the auxiliary dog 59 is adapted to engage an upturned arm 30 upon the dog 29 of the latch-bolt, whereby said dog 29 will be pivotally moved in such a way as to elevate its weighted rear end 31 20 above the upper end 32 of lever 14, so that on the retraction of the latch-bolt said end 31 of the dog 29 will freely pass over the upper end of lever 14 and will not be engaged therewith to stop the rearward movement 25 of the bolt under tension of its spring 33. Simultaneously the cam-surface on the forward side of the finger 63 of the auxiliary dog 59 will ride up on the said weighted rear end 31 of the latch-bolt dog 29 in such a way 30 as to throw the auxiliary dog pivotally upward to disengage the finger 63 thereof from the pointed upper end 32 of lever 14, so that the rearward movement of the bolt is altogether unobstructed. 35 In connection with the mechanism above described I have provided means for holding the bolt 19 locked in its latching position, and, as indicated in Figs. 4, 5, 6, and 7, such means comprises a locking plate or detent 49, 40 extended for sliding movement in a vertical direction beneath the member 46, with its lower end guided for such movement upon a stud 49^b in the casing and its upper end engaged against the supporting-stud 53, where- 45 on the member 46 is rested. The said upper end of detent 49 has a finger 48 for engagement in a notch 47 in member 46 when the detent is upwardly moved, and the lower part of said detent is notched out, as seen at 50, for proper engagement with a key inserted at aperture 18, so that movement of the detent may be effected on turning of said key. The upper end of detent 49 has two notches 49^a, adapted to be successively engaged by a 55 tooth or projection 51 on a tumbler 51^a, pivoted in casing 13 and pressed by a spring 52 to engage its tooth in said notches 49^a of the detent, the tumbler having an edge surface projecting in a well-known way in the path 60 of a key inserted at aperture 18 and turned so that in the turning of said key the tumbler will be moved pivotally primarily to disengage its tooth from a notch 49^a of detent 49, after which the detent will be slid endwise 65 into locking or unlocking position, the spring

52 acting to engage the tooth of tumbler 51^a with the other notch of the detent after the completion of the movement of said detent. By this arrangement it will be seen that when the latch-bolt is thrown into latching position 70 and is held in such position by engagement of the auxiliary bolt with its hooked end so that the member 46, the notch 47 in which was previously out of alinement with the finger 48 of detent 49, is slid forwardly to 75 bring said notch 47 into alinement with said finger, a key may be inserted at aperture 18 and when turned will operate to throw the detent upwardly to engage its finger in notch 47, whereby movement of member 46 relative to the bolt 19, such as is requisite to effect the disengagement of auxiliary bolt 34 from the latch-bolt, is altogether prevented, and consequently the latch-bolt is effectively held in locked position until the key has been 80 reversely turned to disengage finger 48 from the notch of member 46.

For convenience in sliding the door into closed position I have provided in the casing 13 a pull comprising a ring 64, adapted when 90 not in use to be pushed within said casing, as seen in Fig. 4, so that its forward edge is flush with the door-plate 38, said pull-ring having a stem 65 guided on a stud 66 in the casing and actuated by a spring 67, the tension of 95 which is exerted to normally press the ring 64 out from the casing in position for convenient engagement by the fingers, so that the door may be drawn out from its seat in the wall.

68 is a shoulder on stem 65, and 69 is a dog 100 engageable therewith to hold the ring 64 when pushed within the casing against withdrawal therefrom, said dog being pivoted in casing 13 and having an arm 71 and a spring 70 normally pressing the dog in engagement 105 with the shoulder 68.

72 is a push-pin slidable in the casing below the ring 64, with its rear end engageable with the arm 71 of dog 69 and its forward end passed through an aperture in the door-plate 110 38, as seen at 73, so that said forward end may be pressed by the finger in order to throw dog 69 pivotally to disengage it from the shoulder 68 on the stem of ring 64, whereupon spring 67 is permitted to operate to 115 push said ring out from the casing.

For simplicity and economy of construction it may be preferable to construct the casing 13 separately from the door-plate 38, and where this is done I prefer to employ the 120 means shown in Fig. 4 for connecting said parts, said means comprising lugs 39, integral on plate 38 and perforated and projecting inside casing 13, the sides of which have perforations registering with those of lugs 39, so 125 that pins or screws 40 may be passed through such perforations for securely holding the parts together.

Where the improved latch device is used upon double sliding doors, I prefer to provide 130

one door with the casing 13, connected with the door or latch plate 41, as seen in Fig. 10, so that a ring 64^a and push-pin 72^a, similar to that above described, may be held in such 5 casing to permit convenient movement of the door out from the wall. In this construction the auxiliary plate 43^a, carrying auxiliary bolt 34, is similar to the auxiliary plate 43, above described, except that its upper slot 10 45^a is made long enough to receive the upper lug 39^a, by means of which the plate 41 is held to the casing, and its lower slot 45^b is also of increased length to provide for the movement of parts 64^a and 72^a. The upper 15 lug 39^a is also preferably turned into a horizontal position, so as to occupy less space and permit more complete movement of auxiliary plate 43^a in adjusting the position thereof to bring opening 44 in alinement with the latch-bolt on the other door.

From the above description it will be seen that the improved latch constructed according to my invention is of an extremely simple and inexpensive nature and is especially well 20 adapted for use in connection with sliding doors, since there is no projection of the latch-bolt when the door is open, and, furthermore, the actuating means for latching and unlatching the door and also for locking the 25 same are of an extremely simple and inexpensive nature and are not liable to become readily deranged or broken, and it will also be obvious from the above description that the device is capable of considerable modification 30 without material departure from the principles and spirit of the invention, for which reason I do not desire to be understood as limiting myself to the precise form and arrangement of the several parts of the device 35 herein set forth in carrying out my invention in practice.

Having thus described my invention, what I claim, and desire to secure by Letters Patent, is—

45 1. In a device of the character described, the combination of a casing having a face-plate, a bolt housed in the casing with an extremity adapted to play through the face-plate and to stand, when the bolt is retracted, 50 flush with said face-plate, a spring connected with said bolt and arranged to retract it within the casing and means for moving said bolt against the tension of the spring to throw its extremity out from the face-plate.

55 2. In a device of the character described, the combination of a casing having a face-plate, a bolt housed in the casing with an extremity adapted to play through the face-plate and to stand, when the bolt is retracted, 60 flush with said face-plate, a spring connected with the bolt and arranged to retract it within the casing, means for moving the bolt against the tension of the spring to throw its extremity out from the face-plate and a latch-

plate having means for engagement with said 65 extremity of the bolt when thrown out of the casing to hold the bolt in latching position.

3. In a device of the character described, the combination of a casing having a face-plate, a bolt housed in the casing with an extremity adapted to play through the face-plate, means for moving the bolt to throw its extremity out from the face-plate and a latch-plate having means for engagement with said 70 extremity of the bolt when thrown out of the 75 casing to hold said bolt in latching position.

4. In a device of the character described, the combination of a casing having a face-plate, a bolt housed in the casing with an extremity adapted to play through the face-plate, means for moving the bolt to throw its extremity out from the face-plate, a latch-plate and spring-actuated means carried thereby for engagement with the extremity 80 of the bolt when thrown out of the casing to 85 hold the same in latching position.

5. In a device of the character described, the combination of a casing having a face-plate, a bolt housed in the casing with an extremity adapted to play through the face-plate, means for moving the bolt to throw its extremity out from the face-plate and a latch-plate having adjustable means for engagement 90 with said extremity of the bolt when thrown out of the casing. 95

6. In a device of the character described, the combination of a casing having a face-plate, a bolt housed in the casing with an extremity adapted to play through the face-plate, means for moving the bolt to throw its extremity out from the face-plate, a latch-plate having an opening of greater size than and adapted to be traversed by said extremity of the bolt when thrown out of the casing and a plate adjustably held on said latch-plate 100 105 and having means for engagement with said extremity of the bolt to hold the same in latching position.

7. In a device of the character described, the combination of a casing having a face-plate, a bolt housed in the casing with an extremity adapted to play through the face-plate, means for moving the bolt to throw its extremity out from the face-plate, a latch-plate and a part carried thereon and movable 110 115 in and out of engagement with said bolt and adapted, when engaged therewith, to hold the bolt in latching position.

8. In a device of the character described, the combination of a casing having a face-plate, a bolt housed in the casing with an extremity adapted to play through the face-plate, means for moving the bolt to throw its extremity out from the face-plate, a latch-plate, a part carried thereon and movable in 120 125 and out of engagement with said bolt and adapted, when engaged therewith, to hold the bolt in latching position and mechanism

for moving said part to disengage it from the bolt to permit the same to be retracted within the casing.

9. In a device of the character described, the combination of a casing having a face-plate, a bolt housed in the casing with an extremity adapted to play through the face-plate, a spring connected with the bolt to retract the same, means for moving the bolt 10 against the tension of said spring to throw its extremity out from the face-plate, a latch-plate, a part carried thereon and movable in and out of engagement with said bolt and adapted, when engaged therewith to hold the 15 bolt in latching position against the tension of said spring and mechanism for moving said part to disengage it from the bolt to permit the same to be retracted within the casing.
10. In a device of the character described, the combination of a casing, a bolt adapted to be housed therein when in retracted position, a spring connected with the bolt for retracting the same, means outside the casing and 25 adapted for engagement with the bolt for holding it in latching position against the tension of said spring when the bolt is thrown out of the casing and mechanism adapted for successive actuation to first throw said bolt 30 into latching position and to afterward operate said holding means to release the bolt therefrom.

11. In a device of the character described, the combination of a casing, a bolt adapted to be housed therein when in retracted position, a spring connected with the bolt for retracting the same, means outside the casing and adapted for engagement with the bolt for holding it in latching position against the 35 tension of said spring when the bolt is thrown, means for throwing the bolt against the tension of said spring and mechanism for releasing the bolt from said holding means to permit the bolt to be retracted.

12. In a device of the character described, the combination of a casing, a bolt adapted to be housed therein when in retracted position, a spring connected with the bolt for retracting the same, means outside the casing and 40 adapted for engagement with the bolt for holding it when thrown in latching position against the tension of said spring, means for releasing the bolt from said holding means to permit retraction of the bolt out of latching 45 position and mechanism adapted for successive actuation first to throw the bolt against the tension of the spring and in engagement with said holding means and afterward to operate the releasing means to permit the bolt 50 to be retracted within the casing.

13. In a device of the character described, the combination of a casing having a face-plate, a bolt housed in the casing with an extremity adapted to play through the face-

plate, means for moving the bolt to throw its 65 extremity out from the face-plate, a striking-plate, means carried thereby for engagement with said extremity of the bolt when thrown out of the casing to hold the bolt in latching position and means for releasing the bolt 70 from said holding means to permit retraction of the bolt out of latching position.

14. In a device of the character described, the combination of a casing having a face-plate, a bolt housed in the casing with an extremity adapted to play through the face-plate, means for moving the bolt to throw its 75 extremity out from the face-plate, a striking-plate, means carried thereon for engagement with said extremity of the bolt to hold the 80 bolt in latching position when thrown, means for releasing the bolt from said holding means to permit retraction of the bolt out of latching position and a locking device engageable with said releasing means to hold the same 85 from operation.

15. In a device of the character described, the combination of a casing having a face-plate, a bolt housed in the casing with a hooked extremity adapted to play through 90 the face-plate, means for moving the bolt to throw its hooked extremity out from the face-plate, a striking-plate and a spring-pressed auxiliary bolt connected therewith for engagement with the hooked end of said bolt for holding the same when thrown in 95 latching position.

16. In a device of the character described, the combination of a casing having a face-plate, a bolt housed in the casing with a 100 hooked extremity adapted to play through the face-plate, means for moving the bolt to throw its hooked extremity out from the face-plate, a striking-plate, a spring-pressed auxiliary bolt connected therewith for engagement with the hooked end of said bolt 105 for holding the same when thrown in latching position and means carried by the casing and adapted to be thrown therefrom for operative engagement with the auxiliary bolt to 110 release the same from engagement with said bolt to permit the same to be retracted within the casing.

17. In a device of the character described, the combination of a casing having a face-plate, a main bolt housed in the casing with a hooked extremity adapted to play through 115 the face-plate, means for moving said main bolt to throw its hooked extremity out from the face-plate, a striking-plate, a spring-pressed auxiliary bolt connected with said striking-plate for engagement with the hooked 120 end of the main bolt for holding the same when thrown in latching position and a member movable in the casing with an arm adapted, when said member is moved, to be extended through the face-plate into engagement with said auxiliary bolt to move the 125

same to disengage it from the hooked end of the main bolt to permit the same to be retracted within the casing.

18. In a device of the character described, 5 the combination of a casing having a face-plate, a main bolt housed in the casing with a hooked extremity adapted to play through the face - plate, a striking - plate, a spring-pressed auxiliary bolt connected therewith 10 for engagement with the hooked end of the main bolt for holding the same when thrown in latching position, a member movable in the casing with an arm adapted, when the member is moved, to be extended through the 15 face-plate into engagement with said auxiliary bolt to move the same to disengage it from the hooked end of the main bolt and mechanism adapted for successive actuation first to move the main bolt into latching position and afterward to move said member to throw the arm thereof into operative engagement with said auxiliary bolt for the release of the main bolt therefrom.

19. In a device of the character described, 25 the combination of a casing having a face-plate, a main bolt housed therein with an extremity adapted to be thrown out from the face-plate when the bolt is moved into latching position, a dog carried by said bolt, a lever pivoted in the casing and engageable with the dog to move the bolt into latching position, an escutcheon having a movable part and a connection between said movable part on the escutcheon and said lever within the 30 casing for moving the lever in unison with said movable part.

20. In a device of the character described, the combination of a casing, a bolt housed therein with an extremity adapted to be thrown out of the casing into latching posi- 35

tion, a dog carried by said bolt, a lever pivoted in the casing and engageable with the dog to move the bolt into latching position, an escutcheon, an actuating - slide movably mounted on the escutcheon and provided 45 with a socket and a projection on said lever and engaged with said socket of the actuating-slide for moving the lever in unison with said slide.

21. In a device of the character described, 50 the combination of a casing, a bolt housed therein with an extremity adapted to be thrown out of the casing into latching position, a striking-plate an auxiliary bolt carried thereby for engagement with the extremity of the main bolt when thrown into latching position, a member guided for movement on the main bolt and within the casing and having an arm adapted, when said member is moved upon the main bolt, to be ex- 55 tended out from the casing in engagement with the auxiliary bolt to actuate the same for releasing the main bolt, dogs pivoted respectively upon the main bolt and upon the member movable thereon and actuating 60 mechanism comprising a lever engageable on successive operation first with the dog of the main bolt to move the same into latching position and second with the dog of said member for moving the same to engage its arm 65 with the auxiliary bolt for releasing the main bolt.

In testimony whereof I have hereunto signed my name, at Byron, Illinois, this 11th day of May, 1905, in the presence of two sub- 70 scribing witnesses.

GEORGE C. EMMERT.

Witnesses:

HARRY ZELLER,
RAY BARRICK.
